PLASTIC TOILET SEAT HINGE

Harold D. Watson, Beloit, Wis.

Application August 11, 1943, Serial No. 498,154

6 Claims.

(Cl. 4—236)

This invention relates to toilet seat hinges of the type forming the subject matter of the copending application of Harold D. Watson, Serial No. 423,569, filed December 19, 1941.

As in the copending application, it is a broad general object of the present invention to provide a toilet seat hinge formed entirely of a plastic.

More specifically, it is an object of this invention to provide a plastic toilet seat hinge which is reinforced against breakage.

Another object of this invention is to provide a plastic toilet seat hinge so designed and constructed as to have free pivotal motion of the seat and cover members despite possible misalignment of the supporting standards resulting from being mounted on an uneven surface of the toilet bowl.

Still another object of this invention is to provide a plastic toilet seat hinge wherein the parts are formed of a plastic having sufficient elasticity to yield under normal stress and take up the play or clearance in the connections between the parts and thus transfer the stress to the reinforcing member.

A further object of this invention is to provide a toilet seat hinge of the character described which incorporates a reinforcing rod of wood or other suitable material so embodied in the construction as to tie the hinge parts together and reinforce the trunnions by which the hinge members are pivotally mounted in the standards.

With the above and other objects in view, which will appear as the description proceeds, this invention resides in the novel construction, combination and arrangement of parts substantially as hereinafter described, and more particularly defined by the appended claims, it being understood that such changes in the precise embodiment of the herein disclosed invention may be made as come within the scope of the claims.

The accompanying drawings illustrate two examples of the physical embodiment of the invention constructed in accordance with the best modes so far devised for the practical application of the principles thereof, and in which:

Figure 1 is a perspective view of a toilet seat hinge constructed in accordance with this invention and illustrating its manner of use;

Figure 2 is an enlarged longitudinal sectional view through the hinge;

Figure 3 is a cross-sectional view taken through Figure 2 on the plane of the line 3—3;

Figure 4 is a perspective view illustrating all

of the parts of the hinge separated and in their proper order of assembly; and

Figure 5 is a view in side elevation with parts broken away and in section illustrating a slightly modified embodiment of the invention.

Referring now particularly to the accompanying drawings, in which like numerals indicate like parts, the numeral 5 designates the standards of the hinge which are molded of a suitable plastic and have attaching bolts 6 embedded therein. The bolts 6 extend downwardly for passage through the holes in the customary ledge 1 of the toilet bowl to enable the standards to be anchored thereto.

15 Each standard has a transverse bore 8 for the reception of trunnions 9 and 10. The trunnions 9 project from the opposite ends of a cover hinge member 11 and the trunnions 10 project from the inner sides of seat hinge members 12. The combined length of the pair of trunnions 9 and 10 is substantially equal to the length of the bore 8 so that when assembled the bores 8 are substantially fully occupied by the trunnions.

20 The trunnions 10 on the seat hinge members 12 are hollow to receive the end portions of a reinforcing rod 13 embedded in the cover hinge member 11 coaxially with its trunnions 9 or snugly seated in a cored hole extending therethrough coaxially with its trunnions. In any event the 25 reinforcing rod 13 which may be of wood or any other suitable material reinforces the trunnions 9 and projects beyond the ends thereof to protrude through the standards and enter the hollow trunnions 10.

30 It is to be observed that the ends of the reinforcing rod extend a substantial distance into the seat hinge members 12 and beyond their inner faces from which the trunnions 10 project. Consequently, the anchorage of the hollow trunnions 40 10 on their respective cover hinge members is reinforced by the rod.

35 The seat hinge members 12 have attaching flanges 14 which are secured to the under side of the toilet seat by screws or other fasteners. The 45 cover hinge member 11 is similarly secured to the cover by means of a flange 15 provided with apertures for the reception of attaching screws.

Attention is directed to the fact that the trunnions 9 and 10 have substantial play or clearance 50 in the bores 8 and that the projecting ends of the reinforcing rod similarly fit rather loosely in the hollow trunnions 10 and the inward extensions of their bores into the seat hinge members. In view of this clearance, free pivotal motion of the seat and cover members is assured despite the possi-

bility of misalignment of the transverse bores in the standards due to their being mounted on an uneven surface of the toilet bowl.

It is also to be specially observed that the plastic of which the hinge members are made is sufficiently elastic to permit the hinge members to yield under normal stress and thus take up the clearance between the parts to the point where the reinforcing rod carries the load. In this manner the reinforcing rod is effective for its purpose without incurring the objectionable possibility of binding resulting from misalignment of the bores in the standards.

As illustrated in Figure 5, it is also possible to adapt the hinge of the invention to installations where the toilet seat cover is omitted. In this instance, the toilet seat cover hinge member 11 is supplanted with a spreader 16 which may be cylindrical and which spans the distance between the standards and has the reinforcing rod 13 positioned therein in the same manner as the hinge member 11.

The ends of the spreader are formed with flanges 17 providing shoulders to bear against the inner faces of the standards and have trunnions 9' projecting beyond the shoulders to enter the standards in the same manner as hereinbefore described. In other respects, the construction shown in Figure 5 is the same as that of Figures 1 to 4, inclusive.

From the foregoing description taken in connection with the accompanying drawings, it will be readily apparent to those skilled in the art that this invention provides a substantial improvement in plastic toilet seat hinges in that it makes the hinge practically indestructible without the necessity for using critical material and without entailing the possibility of binding or other interference with free pivotal motion of the cover and seat.

What I claim as my invention is:

1. A plastic toilet seat hinge comprising: a pair of standards molded of plastic and each having a transverse bore; attaching bolts on the standards for securing the same to a toilet bowl with their transverse bores substantially coaxial; a pair of hinge members molded of plastic and each having a hollow trunnion projecting from one side and an attaching flange adapted for attachment to a toilet seat with the hollow trunnions of the hinge members facing each other and received in the outer end portions of the transverse bores of the standards; a member molded of plastic and spanning the space between the standards, said member having integral trunnions projecting from the ends thereof and received in the inner end portions of the transverse bores of the standards; a reinforcing rod embedded in said last named member coaxially with its trunnions and projecting from the ends of the trunnions and entering the hollow trunnions on the hinge members whereby said rod ties the entire hinge structure together and reinforces the trunnions.

2. A plastic toilet seat hinge comprising: a pair of standards molded of plastic and each having a transverse bore, attaching bolts on the standards for securing the same to a toilet bowl with their transverse bores substantially coaxial; a pair of hinge members molded of plastic and each having a hollow trunnion projecting from one side and an attaching flange adapted for attachment to a toilet seat with the hollow trunnions of the hinge members facing each other and received in the outer end portions of the transverse bores of the standards; a member molded of plastic and

spanning the space between the standards, said member having integral trunnions projecting from the ends thereof and received in the inner end portions of the transverse bores of the standards; a reinforcing rod embedded in said last named member coaxially with its trunnions and projecting from the ends of the trunnions and entering the hollow trunnions on the hinge members whereby said rod ties the entire hinge structure together and reinforces the trunnions, all of the trunnions having substantial clearance in the transverse bores of the standards and the projecting ends of the reinforcing rod having substantial clearance in the bores of the hollow trunnions projecting from the hinge members to accommodate possible misalignment of the parts due to the standards being mounted on uneven surfaced toilet bowls.

3. A plastic toilet seat hinge comprising: a pair of standards molded of plastic and each having a transverse bore; attaching bolts on the standards for securing the same to a toilet bowl with their transverse bores substantially coaxial; a pair of hinge members molded of plastic and each having a hollow trunnion projecting from one side and an attaching flange adapted for attachment to a toilet seat with the hollow trunnions of the hinge members facing each other and received in the outer end portions of the transverse bores of the standards; a member molded of plastic and spanning the space between the standards, said member having integral trunnions projecting from the ends thereof and received in the inner end portions of the transverse bores of the standards; and a reinforcing rod embedded in said last named member coaxially with its trunnions and projecting from the ends of the trunnions and entering the hollow trunnions on the hinge members whereby said rod ties the entire hinge structure together and reinforces the trunnions, the ends of the reinforcing rod extending into the hinge members beyond their sides from which their hollow trunnions project to reinforce the anchorage of said hollow trunnions.

4. A plastic toilet seat hinge comprising: a pair of standards molded of plastic and each having a transverse bore; attaching bolts on the standards for securing the same to a toilet bowl with their transverse bores substantially coaxial; a pair of hinge members molded of plastic and each having a hollow trunnion projecting from one side and an attaching flange adapted for attachment to a toilet seat with the hollow trunnions of the hinge members facing each other and received in the outer end portions of the transverse bores of the standards; a cover hinge member molded of plastic and spanning the space between the standards, said cover hinge member having integral trunnions projecting from the ends thereof and received in the inner end portions of the transverse bores of the standards; a reinforcing rod embedded in said cover hinge member coaxially with its trunnions and projecting from the ends thereof and beyond the standards with its ends entering the hollow trunnions on the hinge members whereby said rod ties the entire hinge structure together and reinforces the trunnions; and a flange on said cover hinge member adapted for attachment to a toilet seat cover.

5. A plastic toilet seat hinge comprising: a pair of standards molded of plastic and each having a transverse bore; attaching bolts on the standards for securing the same to a toilet bowl with their transverse bores substantially coaxial; a pair of hinge members molded of plastic and each

having a hollow trunnion projecting from one side and an attaching flange adapted for attachment to a toilet seat with the hollow trunnions of the hinge members facing each other and received in the outer end portions of the transverse bores of the standards; a cover hinge member molded of plastic and spanning the space between the standards, said cover hinge member having integral trunnions projecting from the ends thereof and received in the inner end portions of the transverse bores of the standards; a reinforcing rod embedded in said cover hinge member coaxially with its trunnions and projecting from the ends thereof and beyond the standards with its ends entering the hollow trunnions on the hinge members whereby said rod ties the entire hinge structure together and reinforces the trunnions; and a flange on said cover hinge member adapted for attachment to a toilet seat cover; said trunnions having substantial clearance in the bores of the standards and the ends of the reinforcing rod having substantial clearance in the bores of the hollow trunnions on the hinge members to which the toilet seat is fixed to insure freedom of hinge action of the parts notwithstanding such possible misalignment as might result from an uneven toilet bowl top surface and the hinge members having sufficient elasticity to yield under stress and take up the clearance between the parts so that the load causing the stress is transmitted to the reinforcing rod.

6. A toilet seat hinge comprising: a pair of standards each having a transverse bore and a

flat bottom spaced the same distance from the bore; an attaching bolt extending from the bottom of each standard for securing the same to the top of a toilet bowl with the transverse bores of the two standards substantially coaxial; a pair of hinge members each having an attaching flange adapted for attachment to the underside of a toilet seat and having an upstanding boss at one end to be positioned adjacent to the rear edge of the toilet seat, and a hollow trunnion formed integrally with said boss and projecting from the inner face thereof so that said hollow trunnions of the two hinge members project toward each other and into the outer end portions of the transverse bores of the standards to hingedly mount the toilet seat; a cover hinge member of a length to span the distance between the inner faces of said standards, said cover hinge member having a flange adapted for attachment to the underside of a toilet seat cover; a shoulder projecting up from said flange for engagement with the rear edge of the cover to facilitate positioning of the cover on said cover hinge member; hollow trunnions projecting from opposite ends of said cover hinge member and received in the inner end portions of the transverse bores of the standards to hingedly mount the cover; and a reinforcing rod embedded in the cover hinge member and extending for the full length thereof through its hollow trunnions and beyond the ends of its hollow trunnions into the hollow trunnions of the seat hinge members.

HAROLD D. WATSON.
